UNITED STATES PATENT OFFICE.

HARRY D. WETHLING, OF ORANGE, NEW JERSEY.

LOCK.

1,364,665.

Specification of Letters Patent.

Patented Jan. 4, 1921.

Application filed July 9, 1919. Serial No. 309,536.

To all whom it may concern:

Be it known that I, HARRY D. WETHLING, a citizen of the United States, and a resident of Orange, in the county of Essex and State 5 of New Jersey, have invented a new and Improved Lock, of which the following is a full, clear, and exact description.

This invention relates to a permutation lock, and has as an object to prevent the 10 reading of the same when in open position by a person unauthorized to tamper with such lock and who might open the same for his own personal benefit subsequently.

It is a well-known fact that quite a number 15 of thefts, in connection with the opening of permutation locks, have occurred by means of a person, who did not know the combination of the same, reading at different intervals the various numerals to which 20 the dial of such lock was turned, and, subsequently, rotating the dial in a similar manner, whereby to open the same.

While my invention is applicable to any 25 device utilizing a permutation lock, the same is shown in connection with a valve lock.

One drawback exists in connection with a 30 valve lock utilizing a permutation system, in that while the fluid is flowing through the pipe line, any unauthorized person may 35 glance at the various dials controlling the movement of the valves and instantly read the proper combination of the successive valves to permit an uninterrupted flow of fluid through the lock.

I have now constructed a lock of the permutation type wherein it would be possible 40 to actuate the lock so as to open the same and yet leave the dial in such a position that it is impossible for any one to subsequently 45 open such lock.

Reference is had to the accompanying 45 drawings, which illustrate one practical embodiment of my invention, and in which—

Figure 1 is a plan view of a pipe lock embodying my invention;

Fig. 2 is a sectional view taken along line 2—2 of Fig. 1; and

Fig. 3 is a section taken along line 3—3 of Fig. 2.

In these various views like reference numerals designate similar parts, and the reference numeral 1 indicates the body of the 55 lock, through which body there extends a

passage 2 adapted to permit the flow of fluid through the same.

Openings bisecting such passage extend through the body of the lock 1 and have mounted within them ordinary rotatable 60 taper valves 3 provided with openings 4 adapted to permit the flow of fluid therethrough. The body of the valve 3 has its uppermost edge provided with a flange, so as to form a plate 5, centrally from which 65 there extends upwardly a stem 6 which is headed so as to effectively retain in applied position a dial 7, which may be provided with finger-actuating rods 8.

The dial 7 is rotatable around the stem 70 6, and the underside of such dial is preferably provided with a depending annular flange 9 provided at one point in the circumference with a downwardly projecting lug 10. The upper surface of the plate 5 75 is formed plain, with the exception of a lug 11 which extends upwardly and intersects the path of travel of the lug 10.

In operation it will now be appreciated 80 that, assuming that it is desired to open any or all of the valves, the proper combination being known, the dials 7 may be rotated by means of the finger-rods 8 until it is felt that the lugs 10 and 11 are in engagement 85 one with the other. The dial is then rotated 90 until the proper number corresponds with the marking line upon the body of the lock, at which time it is known that the valve is open, and the dial may be given a slight turn to the rear so that it will be impossible 95 for any one unauthorized to inspect such lock to tell which numeral coincides with the opening of the lock or the valve controlled thereby.

As aforesaid, while I have disclosed my 95 invention as applied to a valve lock, I wish it understood that my invention may prove extremely valuable as applied, for instance, to safes, etc.

Further, any number of modifications in 100 construction may well be resorted to without in the least departing from the scope of my invention.

Having thus described my invention, I 105 desire to claim:

1. A lock, including a valve, a plate secured to such valve, a dial mounted upon and rotatable with respect to such plate, such dial being formed with a downwardly-projecting lug, said plate being formed 110

with an upwardly-projecting lug which intersects the path of travel of such first-named lug.

2. A lock, including a valve, a plate associated with such valve, a stem projecting upwardly from such plate, a dial rotatably secured to such stem and positioned above said plate, an upwardly extending lug associated with the upper-face of such plate and a downwardly projecting lug associated with the under-face of the dial and adapted to be capable of engaging the lug associated with the plate.

3. In mechanism of the class described, a series of control devices which have to be 15 in a required predetermined position to effect starting of mechanism controlled, and an indicating disk on each control device, understandable only by an initiated operator to indicate when the particular control device is in the required starting position, and a lost motion connection between each disk and its control mechanism permitting movement of the indicating disk to temporarily conceal its required starting position. 20 25

HARRY D. WETHLING.
